UNITED STATES PATENT OFFICE.

GUST HARMOUTH, OF YALE, OKLAHOMA.

COIN CARD.

Application filed June 6, 1927. Serial No. 196,755.

This invention relates to devices for holding coins or other similar small articles, so that they can be transmitted by mail; and it consists of a card constructed as herein-
5 after fully described and claimed.

In the drawings, Fig. 1 is a front view of a card with a portion of it removed to show the back sheet and adhesive material. Fig. 2 is a similar view of a portion of the card
10 without the back sheet. Fig. 3 is a section through the card, taken on the line 3—3 in Fig. 1.

The coin card is formed of a stiff card 5, and a thin back sheet 10 of paper or other
15 similar material. The card 5 is provided with a series of openings 7 of substantially circular form, and of various size to accommodate different coins. These openings 7 have rectangular offset portions or recesses
20 9, the opposite sides of which are arranged parallel to each other. The card 5 is relatively stiff and thick, but it need not be as thick as the coins for which it is intended. A thin sheet 10 of paper or other similar
25 material is secured against one side of the card 5 over its openings, by adhesive material 12, or by any other approved means. This sheet 10 is provided with slots 14 arranged in pairs, one pair for each opening 7.
30 These parallel slots 14 extend between the corners of the recesses 9, at a right angle to

their parallel sides. A small hole 15 is preferably formed in the back sheet 10 at the end of each slot, and these holes are arranged at the corners of the recesses.

35 A coin 18 is inserted and retained in any one of the openings by springing the portion of the back sheet between its slots forwardly into the opening of the card, and slipping the coin under said portion into the
40 opening, as indicated in Fig. 1. The coin 18 fits loosely in the opening, and can easily be removed and replaced, so that the same card can be used repeatedly.

The small holes 15 add to the flexibility of
45 the paper between the slots, and prevent it from tearing at the ends of the slots.

What I claim is:

A coin card, comprising a relatively stiff card having substantially circular openings provided with offset recesses having parallel sides, and a relatively thin back sheet secured to one side of the card and provided with parallel slots arranged in pairs, each pair of slots being arranged to extend between the recesses of the opening to which it pertains at a right angle to the sides of the recesses.

50 55 In testimony whereof I have affixed my signature.

GUST HARMOUTH.
